HEM BINDING GAUGE

Rose Hoffman, Hartford, Conn.

Application March 3, 1949, Serial No. 79,440

6 Claims. (Cl. 112—137)

1

This invention relates to a hem binding gage for guiding a tape at a fixed distance from a hem, or the like, while the said tape is being sewed adjacent to the hem, and provides an improvement over the hem binding gage disclosed in my co-pending application for United States Letters Patent filed March 26, 1946, Serial No. 657,118 and now Patent No. 2,487,926, dated November 15, 1949.

An object of the present invention is to provide such a hem binding gage which is easy to use and which will, within its capacity, permit selective positioning of a binding tape at any desired distance from a predetermined line.

A further object of this invention is to provide certain improvements which will facilitate the use of the gage.

Further objects and advantages of the invention will be more clearly understood from the following description and from the accompanying drawings in which:

Fig. 1 is a plan view of my improved gage showing the manner in which it is used.

Fig. 2 is a plan view of said gage with the guide plate in a different position.

Fig. 3 is a rear edge view of said gage.

Fig. 4 is a sectional end view on line 4—4 of Fig. 2.

Fig. 5 is a sectional view showing the position of the gage while in use for applying a binding tape to a piece of material.

As illustrated in the drawings, the numeral 5 denotes a piece of material, such as the bottom portion of a garment or the like, on which has been formed a crease 6 defining a hem portion 7 running along the bottom of the skirt, or other garment, and 8 denotes a binding tape or ribbon which is being sewed by means of stitches indicated at 9 to said hem.

In forming the hem, the garment is first marked for length and the crease is then formed along the line defining the bottom edge of the garment. A hem 7 is then formed by sewing the tape 8 along the edge thereof and it is important that this tape be guided, during the sewing thereof onto the hem, so that it will be parallel to the line 6 for the full distance around the garment.

In order to facilitate and render accurate the position of said tape, the present invention provides a gage, preferably in the form of an elongated gage plate 10 having a slot 11 therethrough running longitudinally of said plate and a guide notch 12 in the front edge portion 13.

The said gage includes a guide plate 14 which is slidably secured to the underside of the gage

2

plate 10 by means of a front end portion 15 thereof being turned back over the front edge portion 13 and a rear end portion 16 which is turned over the rear edge portion 17 of the gage plate and has a projecting upright portion 18.

The said guide plate 14 is provided with a guide slot 19 in the portion 18 and a guide slot 20 which is in alignment with the longitudinal slot 11.

My improved gage is preferably graduated along the front edge 13 thereof to denote inches, so that the desired distance of the tape 8 from the preformed line 6 may be determined thereby.

In the use of my improved gage, the tape 8 is first inserted through the slot 19 and then passed downwardly through the slots 11 and 20. The front end of said tape is then extended forwardly of the gage as clearly shown in Figs. 1 and 5.

The guide plate 15 is then moved to the desired distance from the notch 12, which distance may be selected by means of the graduations along the front edge 13. The gage is then held with the fingers in the position illustrated in Fig. 5 and with the notch 12 on the line 6. The leading portion of the tape 8 is then started under the needle of the sewing machine and sewed to the hem by means of the stitches 9.

As the tape and the portion 7 is moved forwardly by the sewing machine, during the sewing operation, the guide notch 12 is maintained on the line 6 and the tape 8 may be tensioned by placing a finger upon said tape and pressing it against the top of the plate 10 while the said plate is held with the hand.

In order to retain the guide plate on the gage plate 10, abutments 21—21 may be formed in said gage plate, adjacent to the opposite ends thereof, to engage the sides of the guide plate and prevent it from becoming detached therefrom.

I claim:

1. A tape gage comprising a plate having an elongated slot extending therethrough, and a guide plate slideable on said gage plate and having a slot in alignment with said elongated slot for guiding a tape through said gage.

2. A tape gage comprising an elongated gage plate having a slot extending longitudinally therethrough, and a guide plate slideable on said gage plate and having a slot in alignment with said elongated slot and a separate slot for guiding a tape through said gage.

3. A tape gage comprising a gage plate having an elongated slot along a front edge portion thereof, a guide notch in said edge portion, a guide plate located under said gage plate and slideable thereon, and means including a slot in

said guide plate aligned with said elongated slot for guiding a tape through said gage at a selected distance from said notch.

4. A tape gage comprising an elongated plate having a slot running longitudinally therethrough along a front edge portion thereof and a notch in said front edge portion, a guide plate mounted under said gage plate and slideably attached thereto by means of edge portions of said guide plate being bent over the marginal portions of said gage plate, and means including a slot in said guide plate aligned with the elongated slot in the gage plate for guiding a tape through said gage at a desired distance from said notch.

5. A tape gage comprising a gage plate having an elongated slot running along the front edge portion thereof and a guide notch in said edge portion, a guide plate located under said gage plate and having a front end portion bent over and upon the front edge portion of the gage plate between the elongated slot and the free edge thereof, a rear portion bent over the rear edge portion of the gage plate, an upright portion ex-

15 tending vertically on the gage from the said rear portion of the guide plate, and means comprising a slot through said upright portion and a separate slot in said guide plate aligned with the elongated slot in the gage plate for guiding a tape through said gage at a desired distance from said notch.

6. A tape gage as set forth in claim 5, wherein the gage plate is provided with abutments adjacent the opposite sides thereof to prevent disengagement of the guide plate therefrom.
